(57) **CLAIM**

The ornamental design for a drainage grate, as shown and described.

DESCRIPTION

FIG. 1 is a perspective view of a new and ornamental drainage grate;

FIG. 2 is a front elevation view thereof;

FIG. 3 is a rear elevation view thereof;

FIG. 4 is a first side elevation view thereof;

FIG. 5 is a second side elevation view thereof; and,

FIG. 6 is a top plan view thereof.

The broken lines show portions of the drainage grate that form no part of the claimed design.
